Letters Patent No. 2380. Dated Aug. 14. 1866.

Design for a Coffin Handle

The schedule referred to in this Letter Patent and making part of the same.

To all whom it may concern:

Be it known that S. D. D. Arnold of New
Britain, Hartford County, and State of Connecticut have inven-
ted a new and Improved Design for a Handle to Coffins, and other
burial cases; and I do hereby declare that the following is a
full, clear, and exact description thereof, which will enable others
skilled in the art, to make and use the same, reference being had
to the accompanying drawing forming part of this Specification.

The present invention relates to a new Design for
a handle to be used more especially upon coffin, burial
cases or caskets, and other similar receptacles employed for
the burial of the dead and in the accompanying plate
this Design is illustrated, the

Figure being a photographic view of the same.
It, in the plate represents the handle which in its de-
sign consists of a hand B, secured to a head plate or sup-
port C, which hand is represented as grasping by, and
in its fingers D, a rod E.

I claim as new, and desire to secure by Letters Patent
The Design herein described, and shown in the accompan-
ying plate.

Witnessed,

Chas. Beck.

Edwrd de. Poirier.
